UNITED STATES PATENT OFFICE.

WILLIAM H. JOHNSON, OF WHITMAN, MASSACHUSETTS, ASSIGNOR OF
ONE-FOURTH TO DAVID B. GURNEY, OF WHITMAN, MASSACHUSETTS.

NAIL-SORTING MACHINE.

No. 833,688.

Specification of Letters Patent.

Patented Oct. 16, 1906.

Application filed October 22, 1904. Serial No. 229,591.

To all whom it may concern:

Be it known that I, WILLIAM H. JOHNSON, a citizen of the United States, residing at Whitman, in the county of Plymouth and State of Massachusetts, have invented certain new and useful Improvements in Nail-Sorting Machines; and I do hereby declare the following to be a full, clear, and exact description of the invention, such as will enable others skilled in the art to which it appertains to make and use the same.

This invention relates to improvements in machines for sorting nails.

The object of the invention is to produce a machine for use in the manufacture of nails, tacks, screws, and the like which will assort the finished articles or the blanks from which they are made, separating from the perfect articles all which are imperfect by reason of defects in the diameter or thickness of the head or in the diameter or form of the shank.

To the above end the invention consists in the machine hereinafter described and claimed.

In the drawings accompanying this specification, Figure 1 is a plan view of a machine embodying the invention with certain of the parts, including the hopper, removed to show the underlying parts. Fig. 2 is a vertical section on line xx , Fig. 1. Fig. 3 is a vertical section of a part of the mechanism shown in Fig. 2, but with the parts in different positions. Fig. 4 is a sectional detail of the raceways, and Fig. 5 is a sectional detail of the bars for separating nails with heads of excessive thickness.

The illustrated embodiment of the invention is adapted particularly to operate on nails or nail-blanks, and it is made in multiplex form. The machine comprises generally a hopper containing the supply of nails, inclined raceways leading therefrom, gaging and separating devices into which the nails are delivered from the raceways, and suitable mechanism, including a shaft and cams for actuating the parts.

The frame of the machine comprises end portions 1 1, a front girder 2, and tie-rods 3 and 4, connecting the ends.

The hopper 5 extends across the machine and is pivoted at 6 upon the end of the frame. A bell-crank lever 7, pivoted upon the tie-rod 3, carries a cam-roll engaging a cam 8 upon the main shaft 9. The upper

end of the lever bears against a projection 55 from the bottom of the hopper and serves to agitate the hopper to facilitate the passage of nails therefrom. The nails are delivered from the front of the hopper, passing beneath a gate 10 and falling upon deflectors 60 11, which have inclined surfaces which direct the nail into the raceways 12, formed by bars 13, supported upon cross-bars 14, secured at their ends to the ends of the frame. The nails hang by their heads in the slots formed 65 by the contiguous sides of the bars 13 and descend by gravity toward the bottoms of the raceways. Such nails as fail to fall into the raceways will pass beyond the lower ends of the deflectors and will then fall between 70 the raceways upon a tray 15, secured below the raceways. Any nails of which the heads are of insufficient diameter will fall entirely through the raceways, and thus be separated from the other nails.

In order to feed the nails one by one to each of the gaging and separating mechanisms, two oscillating fingers are used at the bottom of each raceway. The fingers 16 and 17 are secured to shafts 18 and 19, respectively, journaled at their ends in the frame. To these shafts are fixed cam levers 20 and 21, carrying cam-rolls engaging cams 22 and 23 on the main shaft. The cams are arranged to give alternate movements to the 85 fingers, each finger 16 first oscillating to the left and permitting the lowest nail in the raceway to fall into the notched end of the finger 17 and then moving back to the position shown in Fig. 2, so as to retain the rest of the 90 nails, while the finger 17 oscillates to the left and permits the nail held thereby to fall into the gaging devices.

The gaging and separating devices comprise means for separating nails having heads 95 of excessive diameter, shanks which are crooked or of excessive diameter, or heads which are of excessive thickness.

The means for gaging the diameter of the head are constructed as follows: Two gage-bars 24 and 25, extending longitudinally of the machine, are mounted at their ends in slide-guides 26 in the frame to permit a horizontal movement of the bars. The bars have openings formed in their contiguous faces 100 and gage-plates 27 secured therein. The passage 28, formed between each pair of gage-plates, is of a diameter just equal to that of a

perfect nail-head. The upper portions of the passages are conical, so as to guide the nails surely to the gage-plates, and the bar 25 has slots 29 to permit the entrance of the shanks 5 of the nails in passing from the raceway. Nails having heads of proper diameter will pass through the passages, but nails having heads of excessive diameter will be caught therein, as shown in Fig. 2. In order to separate 10 such a nail from the perfect nails, means are provided for moving the gage-bars to the left and then releasing the nail by separating the bars, thereby permitting the nail to drop upon a plate 30, by which it is directed to a 15 suitable receptacle. In the bar 24 are fixed stems 31, passing loosely through holes in the bar 25 and connected by links 32 to levers 33, pivoted on the tie-rod 4. The lower ends of the levers are connected by adjustable 20 links 34 to cam-levers 35, pivoted upon the tie-rod 3 and carrying cam-rolls engaging cams 36 on the shaft. Fixed in the bar 25 are stems 37, passing loosely through holes in the bar 24. Springs 38, surrounding the 25 stems 37, bear against the bar 24 and against nuts on the stems and hold the bars 24 and 25 normally in contact. When the bars are moved by means of the connections above described to the left, the ends of the stems 37 30 engage during the latter portion of such movement adjustable stops 39, screwed in the girder 2. Thus the movement of the bar 25 is arrested, while the bar 24 continues to move enough farther to release the nails 35 from the passages.

The means for gaging the shanks of the nails comprise gage-bars 40 and 41, supported at their ends in vertical slide-guides 42 in the frame of the machine. Openings 40 are formed in the contiguous faces of the bars 40 and 41 and through the lower part of the latter, and gage-plates 43 are inserted in these openings, and each pair of gage-plates form between them a passage just sufficient to admit a straight shank of the proper diameter. A perfect nail will enter the passage until the head of the nail is seated in a recess at the upper end thereof, entirely below the upper surface of the gage-plates. If, however, the 45 nail has a shank crooked or of excessive diameter, it will not fully enter the passage, but will remain projecting upward therefrom, as at 44. In order to remove such a nail from the passage and separate it from the perfect 50 nails, means are provided for seizing the nail, while the bars 40 and 41 are moved downward to withdraw the nail from the passage, and the nail is then transferred to the left and allowed to fall upon the plate 30. To 55 the bottom of the bar 24 is fixed a clutch-jaw 45, extending along the length of the bar. A co-operating clutch-jaw 46 is supported at its ends by gibs 25*, fixed to the bar 25, so as to be held against the bottom of the bar, but free 60 to move horizontally with respect thereto.

Pins 48, fixed to the jaw 46, may be engaged when the parts are in the position shown in Fig. 2 by screws 49, carried by cam-levers 50, pivoted upon the tie-rod 4. The cam-levers 50 carry cam-rolls engaging cams 51 on the 70 shaft. After the nail has been permitted to drop into the passage the above-described mechanism operates to move the clutch-jaw 46 to the left, so as to grip the projecting portion of the nail between the clutch-jaws. 75 The bars 40 and 41 are then moved downward by means of bell-crank levers 52, connected at 53 to the bar 41 and pivoted upon the tie-rod 4, the bell-crank levers being operated by adjustable connections 54 with 80 cam-levers 55, pivoted upon the tie-rod 3 and actuated by a cam 56 upon the main shaft. This downward movement of the bars releases such portion of the shank of the nail as may have entered the passage, 85 and in the subsequent horizontal movement of the bars 24 and 25, which has already been described, the nail is transferred by the clutch-jaws to a position over the plate 30, the jaw 46 during this movement being 90 held frictionally in operative engagement with the nail. At this point pins 57, fixed in the clutch-jaw 46 and passing loosely through openings in the clutch-jaw 45, engage adjustable stops 58 in the girder 2 and arrest the 95 movement of the clutch-jaw 46, so as to release the nail. After the above-described operation has taken place and the bars 40 and 41 are in their lowered position nails with perfect shanks, which have been 100 retained in the passage, are released by a slight horizontal movement of the bar 40, by which the passage is widened sufficiently to admit the heads of such nails. Stems 59, fixed in the bar 40, pass loosely through 105 sleeves in the bar 41 and carry at their outer ends arms 60, with pins 61 projecting in the paths of movement of the levers 33. Springs 62 keep the bar 40 moved normally to the right, as shown in Fig. 2; but when the levers 110 33 move to the left to impart horizontal movement to the bars 24 and 25 the pins 61 are engaged thereby, and the bar 40 is moved to the left and the nails released. The nails 115 next fall through passages in a bar 63, which is supported at its ends in horizontal slide-guides 64 on the frame of the machine. Below each passage in the bar 63 is a slot formed by two adjacent bars 65 and 66, carried, respectively, by longitudinal bars 67 and 68. The 120 nails pass entirely through the passages and hang in the slots by their heads. Hardened-steel bushings 69 are inserted in each passage, and between the bottom of each bushing and the tops of the bars forming the 125 slot is a space just sufficient to admit a nail-head of normal thickness. After the nail has fallen into the slot a horizontal movement to the left is imparted to the bar 63. The means for doing this comprise an adjustable 130

link 70, pivoted to the bar 63 and to a cam-lever 71, which is pivoted upon the tie-rod 3 and has a cam-roll engaging a cam 72 on the main shaft. When the bar 63 is moved to the left, any nails having heads of excessive thickness will be moved with it, as the heads will project somewhat into the bushings, while nails with perfect heads will remain in the position shown at 73, Fig. 2. The bar 68 is secured to the frame by screws 74 (see Fig. 5) passing through elongated openings in the bar. The means for imparting longitudinal movement to the bar, so as to carry the bars 66, secured thereto, away from their companion bars 65, and thus to release the nails hanging in the slots, comprise a lever 75, pivotally connected to the bar 68. The lever 75 is pivoted at 76 on a hanger secured to the tie-rod 4 and carries a cam-roll engaging a cam 77 on the shaft. When the bar 68 is moved as described, the perfect nails hanging in the slots will fall upon a plate 78 and be directed thereby into a suitable receptacle, while the nails with heads of excessive thickness will fall upon a plate 79 and be directed into another receptacle.

Although the illustrated embodiment of the invention is arranged to gage the nails in several dimensions, it will be understood that the invention in some aspects may be embodied in machines capable of separating nails imperfect in only one or a part of the characteristics with regard to which the present machine operates. Thus where the thickness of the nail-head is immaterial the means for gaging the thickness may be omitted. Moreover, the invention is not limited to the precise details of construction and operation set forth in connection with the description of the preferred embodiment, but may be embodied in other forms broadly defined by the claims.

Having now described the invention, what is claimed is—

1. A nail-sorting machine, having, in combination, a gage with a passage of a diameter substantially equal to the diameter of a perfect nail-head, the gage operating to arrest nails with heads of excessive diameter, and having provision for releasing nails so arrested, and means for feeding nails singly to the gage, substantially as described.

2. A nail-sorting machine, having, in combination, a gage comprising two separable portions forming between them a passage of a diameter substantially equal to that of a perfect nail-head, means for moving the gage laterally and separating its portions to separate and release a nail arrested in the gage, and means for feeding nails singly to the gage, substantially as described.

3. A nail-sorting machine, having, in combination, a gage comprising two separable portions forming between them a passage for nails of which the upper part is tapering and

the lower part of a diameter substantially equal to that of a perfect nail-head, means for separating the portions of the gage to release a nail arrested therein and means for feeding nails singly to the gage, substantially as described.

4. A nail-sorting machine, having, in combination, means for separating nails with imperfect shanks comprising a gage with a recess of substantially the size of a perfect shank, means for seizing and holding a nail which projects from the gage owing to the shank not properly entering the said recess, means for separating the gage and the nail-holding means to withdraw such imperfect nail from the gage, and means for feeding nails singly to the gage, substantially as described.

5. A nail-sorting machine, having, in combination, a shank-gage comprising separable portions, means for removing imperfect nails from the gage, and means for separating the portions of the gage to release nails with perfect shanks, substantially as described.

6. A nail-sorting machine, having, in combination, a shank-gage, means for seizing and holding a nail which projects from the gage owing to the shank not fully entering the gage, means for lowering the gage to withdraw the nail therefrom, means for moving the nail-holding means laterally, means for opening the nail-holding means to release the nail, and means for feeding nails singly to the gage, substantially as described.

7. A nail-sorting machine, having, in combination, means for separating nails with heads of excessive thickness comprising means for supporting the nails, a member located in position to engage the heads of such imperfect nails and to move the nails while remaining inoperative with respect to other nails, and means for feeding nails singly to said separating means, substantially as described.

8. A nail-sorting machine, having, in combination, means for separating nails with heads of excessive thickness comprising means engaging the under sides of the heads for loosely holding the nails so as to permit lateral movement thereof, separating means moving at such distance from the holding means as to engage such heads as are of excessive thickness and move the nails laterally to separate them from the perfect nails, and means for feeding nails singly to the separating means, substantially as described.

9. A nail-sorting machine, having, in combination, means for separating nails with heads of excessive thickness, comprising bars forming a channel in which the nails hang by their heads, means for engaging heads of excessive thickness and moving the nails laterally, and means for separating the bars to release the nails, substantially as described.

10. A nail-sorting machine, having, in combination, an inclined raceway in which the nails are suspended by their heads a finger

having a notched end in which the lowermost nail may hang by its head, means for moving the finger laterally at the proper time to release and feed the nail, and means for holding the remaining nails in the raceway during such feeding movement, substantially as described.

In testimony whereof I affix my signature in presence of two witnesses.

WILLIAM H. JOHNSON.
